DISPOSABLE CULTURE DEVICE

William Robert Winter, Columbus, Ohio, assignor to
Abbott Laboratories, North Chicago, Ill.

Filed Nov. 6, 1972, Ser. No. 304,888

Term of patent 14 years

Int. Cl. D24—02; D9—04

U.S. Cl. D32—1

FIG. 1

FIG. 2

FIG. 3

FIG. 4

FIG. 1 is a perspective view of a disposable culture device showing my new design;

FIG. 2 is a side plan view;

FIG. 3 is a perspective view of the device with the cover removed; and

FIG. 4 is a perspective view showing the separate parts of the device.

I claim:

The ornamental design for a disposable culture device, substantially as shown and described.
